HINGE

Fred G. Bates, Highland Park, Mich.

Application April 4, 1934, Serial No. 718,956

6 Claims. (Cl. 16—164)

This invention relates to improvements in hinges, and refers more particularly to hinges of the concealed type. It is an object of the invention to provide a strong and durable form of hinge of this type which is cheap and simple to manufacture, and wherein the two hinge plates may be moved through substantially 180 degrees to one another.

Another object of the invention is to provide a hinge of this type wherein the two plates are apertured, an arm is pivoted in each aperture and has its outer extremity slidably mounted in the aperture of the other plate, and wherein means are provided intermediately of the ends of the arms for controlling their path of movement as the two plates are turned relative to one another.

A further object of the invention is to provide a hinge wherein the means for controlling the path of movement of one arm is carried by the other arm, so that for a portion of their length the two arms are in vertical alignment at all positions of the plates relative to one another.

Having thus briefly stated some of the objects and advantages of the invention, I will now proceed to describe an embodiment thereof in detail with the aid of the accompanying drawings, in which:

Figure 1 illustrates a front elevation of the hinge when open.

Figures 2 and 3 are sections on the lines 2—2 and 3—3 respectively of Figure 1.

Figure 4 is a section on the line 4—4 of Figure 5, showing the hinge closed, and

Figures 5 and 6 are sections on the lines 5—5 and 6—6 respectively of Figure 4.

Referring to the drawings, 1 and 1a designate two identical vertically disposed hinge plates one of which is shown attached to a door A and the other to a door frame B as by screws 12. Through each of the plates 1 and 1a an aperture 2, or 2a, is formed. In the construction shown in the drawings these apertures extend through the sides of the plates 1 and 1a which are adjacent one another when the hinge is in open position. Formed integral with the plates 1 and 1a are rearwardly disposed horizontal flanges 3 and 3a which form walls around portions of the apertures 2 and 2a. These flanges 3 and 3a are housed in openings C and D formed in the door A and door frame B respectively.

A vertical hinge pin 4, or 4a, extends vertically across each aperture 2, or 2a, adjacent its open side, and the extremities of the pin are

supported in opposed portions of the flange 3, or 3a. Pivoted on the pin 4, or 4a, is a curved arm 5, or 5a, the outer extremity of which is outwardly flared as shown at 6, or 6a. Extending vertically through the outwardly flexed arm extremity 6, or 6a, is a sliding pin 7, or 7a.

Formed diagonally through opposed portions of the flange 3, or 3a, are vertical slotted guideways 8, or 8a, which are rearwardly and outwardly inclined from one another when the hinge is in open position as shown in Figures 1, 2 and 3. The pin 7 is slidable in the guideway 8a, and the pin 7a in the guideway 8. Thus as the angularity of the plates 1 and 1a to one another is varied the pins 7 and 7a travel along their guideways 8a and 8 respectively.

In order to insure corresponding movement of the two arms 5 and 5a so that the pins 7 and 7a are at all times corresponding distances along 20 their guideways 8a and 8, and to control the path of movement of these arms slidable interconnecting means between them are provided. Extending vertically from the arm 5, or 5a, towards its outer flexed extremity 6, or 6a, is 25 a control pin 9, or 9a, which is slidable in a vertical control slot 10a, or 10, formed in the arm 5a, or 5, intermediately of its length.

It will thus be seen that when the hinge is closed, as shown in Figures 4, 5 and 6, only small 30 portions of the arms 5 and 5a between the control pins 9 and 9a, which are then only a short distance apart, are in vertical alignment. As the hinge is opened uniform movement of both pins 7 and 7a along their guideways 8a and 8 is 35 insured by the control pins 9 and 9a until the plates 1 and 1a are substantially in horizontal alignment and the hinge is fully open. Then the intermediate portions of the arms 5 and 5a for the greater portion of their length are in 40 vertical alignment.

In the construction shown in the drawings, the arm 5 is movable between two portions of the arm 5a which is bifurcated. The flexed form of the extremities 6 and 6a of the arms 5 and 5a 45 permits the provision of extensions 5b and 6b at both vertical extremities of both arms. These extensions project vertically so as to form bearings for the hinge pins 4 and 4a and the sliding pins 8 and 8a for substantially their entire 50 height.

While in the foregoing the preferred construction of the invention has been described and shown it is understood alterations and modifications may be made thereto provided the said 55

alterations and modifications fall within the scope of the appended claims.

What I claim is:

1. A hinge comprising two apertured plates, a curved arm pivoted in each plate, both arms being of similar radius for a greater portion of their length and being aligned with one another for a portion of their length in all positions of the hinge, means extending from each arm slidable in a slot formed in the other arm, and guide means carried by the plates each controlling the path of movement of one of the arms. 5
2. A hinge comprising two apertured plates, a curved arm pivoted adjacent one extremity in each plate, both arms being of similar radius for a greater portion of their length and being aligned with the other arm for a portion of their length in all positions of the hinge, means extending from each arm slidable in a slot formed 10 in the other arm, said plates having diagonal slots formed therein, and guide members extending from the unpivoted extremities of the arms slidable in said slots. 15
3. A hinge comprising two apertured plates, a curved arm pivoted adjacent one extremity in each plate, both arms being of similar radius for a greater portion of their length and being aligned with one another for a portion of their length in all positions of the hinge, means extending from each arm slidable in a slot formed 20 in the other arm, said slots being concentric with the portions of the curved arms in which they are formed, and guideways carried by the plates controlling the path of movement of the unpivoted extremities of the arms. 25
4. A hinge comprising two apertured plates, a curved arm pivoted in each plate adjacent one 30 extremity, both arms being of the same radius for the greater portion of their length so that when the hinge is open the radial arm portions are in alignment throughout the greater portion of their length, said arms having radial slots 35 formed therein concentric with the radial arm portions in which they are formed so that the slots in the aligned portions are themselves in alignment, means extending from each arm adjacent one extremity of its radially curved portion slidable in the radial slot in the other arm, and guide means carried by the plates controlling the path of movement of the unpivoted extremities of the arms. 40
5. A hinge comprising two plates, a curved arm pivoted in each plate, both arms being of similar radius for a greater portion of their length and being aligned with one another for a portion of their length in all positions of the hinge, means extending from each arm adjacent its extremity remote from its pivoted end slidable in a slot formed in the other arm, and guide means in said plates each controlling the path of movement of one of the arms. 45
6. A hinge comprising two plates, a curved arm pivoted adjacent one extremity on each plate, both arms being of similar radius for a greater portion of their length and being aligned with the other arm for a portion of their length in all positions of the hinge, means extending from each arm adjacent its extremity remote from its pivoted end slidable in a curved slot formed in the other arm, and guide means carried by the plates controlling the path of movement of the unpivoted ends of the arms. 50

FRED G. BATES.
